(57) **CLAIM**

The ornamental design for a firearm with grenade launcher, as shown and described.

DESCRIPTION

FIG. 1 is a left perspective view of a firearm with grenade launcher showing my new design.

FIG. 2 is a right side view of the firearm of FIG. 1;

FIG. 3 is a left side view of the firearm of FIG. 1;

FIG. 4 is a top view of the firearm of FIG. 1;

FIG. 5 is a bottom view of the firearm of FIG. 1;

FIG. 6 is a front view of the firearm of FIG. 1;

FIG. 7 is a rear view of the firearm of FIG. 1;

FIG. 8 is a left side perspective view of the firearm of FIG. 1 shown with the stock in an alternate position;

FIG. 9 is a right side view of the firearm of FIG. 8;

FIG. 10 is a left side view of the firearm of FIG. 8;

FIG. 11 is a top view of the firearm of FIG. 8;

FIG. 12 is a right side perspective view of a second embodiment of FIG. 1.

FIG. 13 is a top view of the firearm of FIG. 12;

FIG. 14 is a right side perspective view of the firearm of FIG. 1 shown with the hinged stock in a pivoted position;

FIG. 15 is a right side view of the firearm of FIG. 14;

FIG. 16 is a left side view of the firearm of FIG. 14;

FIG. 17 is a top view of the firearm of FIG. 14;

FIG. 18 is a rear view of the firearm of FIG. 14;

FIG. 19 is a left side perspective view of the firearm of FIG. 1 shown with the grenade sight in a deployed position;

FIG. 20 is a left side view of the firearm of FIG. 19;

FIG. 21 is a front view of the firearm of FIG. 19; and,

FIG. 22 is a rear view of the firearm of FIG. 17.
